(71) Applicant: **Spinal Surgical Strategies LLC**,
Denver, CO (US)
(72) Inventors: **Jeffrey B. Kleiner**, Denver, CO (US);
Edward John Grimberg, Jr., Golden,
CO (US)

(73) Assignee: **Spinal Surgical Strategies, LLC**,
Incline Village, NV (US)

(**) Term: **15 Years**

(21) Appl. No.: **29/542,927**

(22) Filed: **Oct. 19, 2015**

(51) LOC (10) Cl. **24-02**

(52) U.S. Cl.

(74) *Attorney, Agent, or Firm* — Sheridan Ross P.C.

(57) **CLAIM**

The ornamental design for a bone graft delivery tool, as shown and described.

DESCRIPTION

FIG. 1 is a front perspective view of the bone graft delivery tool;

FIG. 2 is a front perspective exploded view thereof;

FIG. 3 is a top plan view thereof;

FIG. 4 is a front elevation view thereof;

FIG. 5 is a right elevation view thereof;

FIG. 6 is a bottom plan view thereof;

FIG. 7 is a rear elevation view thereof;

FIG. 8 is a left elevation view thereof;

FIG. 9 is a detailed view of a portion of the bone graft delivery tool of FIG. 1; and,

FIG. 10 is a cross-sectional view of Section A-A of FIG. 9.

1 Claim, 5 Drawing Sheets
